Primary Examiner — Dominic V Simone

(74) Attorney, Agent, or Firm — Banner & Witcoff, Ltd.

(57) CLAIM

The ornamental design for a shoe, as shown and described.

DESCRIPTION

FIG. 1 is a side view of a shoe showing my new design;

FIG. 2 is a front perspective view thereof;

FIG. 3 is a front view thereof;

FIG. 4 is an opposite side view thereof;

FIG. 5 is a rear perspective view thereof; and,

FIG. 6 is a top view thereof.

The curved oblique shade lines represent transparent or translucent material. The broken lines depicting the remainder of the shoe show features that form no part of the claimed design.
